UNITED STATES PATENT OFFICE.

JOHN S. WHEELER, OF DUNSMUIR, CALIFORNIA.

PIPE-BENDING MACHINE.

1,206,743.

Specification of Letters Patent. Patented Nov. 28, 1916.

Application filed July 13, 1915. Serial No. 39,598.

To all whom it may concern:

Be it known that I, JOHN S. WHEELER, a citizen of the United States, residing at Dunsmuir, in the county of Siskiyou and 5 State of California, have invented certain new and useful Improvements in Pipe-Bending Machines, of which the following is a specification.

This invention has relation to machines 10 for bending pipe, rods, bars and the like into fanciful shapes according to the article to be formed and the design to be followed.

The invention provides a machine which may be readily adapted for a variety of 15 curves and for different sizes of material, such adaptation being capable of being easily and quickly effected.

A further purpose of the invention is the provision of means whereby the material 20 may be firmly secured during the process of bending or shaping, the securing means being of a nature to be easily and conveniently manipulated and to adapt itself within certain limits to different sizes of material.

25 With these and other objects in view, which will readily appear as the nature of the invention is better understood, the same consists in the improved construction and novel arrangement and combination of parts 30 which will be hereinafter fully described and particularly claimed.

In the accompanying drawings has been 35 illustrated a simple and preferred form of the invention, it being, however, understood that no limitation is necessarily made to the precise structural details therein exhibited, but that changes, alterations and modifications within the scope of the invention as claimed may be resorted to when desired.

40 Referring to the drawings,—Figure 1 is a top plan view of a pipe bending machine embodying the invention; Fig. 2 is a front view thereof; Fig. 3 is a sectional elevation, the plane of the section being indicated by 45 the line 3—3 of Fig. 1; Fig. 4 is a section on the line 4—4 of Fig. 1; Fig. 5 is a top plan view of an end portion of the machine; Fig. 6 is a detail view of an end portion of one of the clamp operating levers; Fig. 7 is a detail 50 view of the presser piece.

Corresponding and like parts are referred to in the following description and indicated in all the views of the drawings by the same reference characters.

55 The machine embodies a base 1 which preferably consists of a plate but which may

be of any construction to form a substantial support for the several parts. The frame of the machine embodies an upper plate 2 and a lower plate 3, such plates being vertically spaced and adapted to receive between them forms 4 and 5 which are of similar formation but of different diameters, thereby adapting the machine for bending the material upon a greater or less curve. The forms 4 and 5 60 are located at opposite ends of the machine and each preferably consists of a disk which is grooved in its outer edge to form a seat for the work. The shape and size of the groove will depend upon the cross sectional 65 outline of the material to be shaped. The forms 4 and 5 are adapted to be easily and quickly removed so as to be substituted by others of different shape or size. A plurality of clamps are disposed at opposite sides of 70 the machine for holding the work firmly to prevent possible slipping during the bending operation. These clamps are of like formation and a single operating lever may serve as actuating means for opposed clamps. 75 Each of the clamps comprises a fixed jaw 6 and a movable jaw 7, the latter being formed with an arm 8 to which a link 9 is adapted to be adjustably connected, such link having an eye 10 at its free end to receive a bolt or pin 11 by means of which the link is connected to an operating lever 12.

The lower end of the operating lever 12 is bifurcated to receive the link 9 and each bifurcation is provided upon its outer side 90 with a hub 13 which forms a journal by means of which the operating lever is mounted in a bearing 14 which is secured to the upper side of the frame. The bearing 14 comprises spaced members between which the pivot end of the operating lever 12 is received, each of the members being formed with an opening to receive the hub 13. The bolt, or pin, 11 is arranged to one side of the axis of the hubs 13 and extends across the space formed between the members comprising the furcate end of the operating lever. When the link 9 is connected to the operating lever the movable jaw is opened or closed according to the direction in which the free end of such lever is moved.

The jaws 6 and 7 may be slightly resilient if preferred so as to adapt themselves to variations in the size of the work to be clamped. The arm 8 may likewise be resilient, thereby holding the work firmly at all times by a predetermined pressure. The

end of the link 9 connected with the arm 8 is threaded and receives a pair of nuts 15 between which the arm 8 is held. By properly adjusting the nuts 15 the position of 5 the arm 8 may be adjusted so that when the work is firmly gripped the operating lever 12 may occupy a position with the link 9 in line with the axis of the hubs 13, thereby resulting in the clamp being locked so as to 10 prevent casual release of the work. This arrangement of the parts avoids the use of usual means for holding the operating lever 12 in locked position when the clamp is closed to grip the work. It will be understood 15 that a single operating lever 12 is provided for two clamps which have an opposite arrangement. One clamp only is connected at a time with the operating lever but if preferred the links of opposed clamps 20 may be attached at the same time so that both clamps upon opposite sides of the machine may be operated simultaneously. The movable jaws 7 upon the same side of the machine are mounted upon a rod 16 which is 25 common to all the clamps upon one side. This rod passes through bearings 17 secured in any manner to the frame, a pair of such bearings being provided for each of the movable jaws and located upon opposite 30 sides thereof to hold the movable jaws in a given position with reference to the fixed jaws.

The presser piece 18 is oblong and formed in its sides with a plurality of longitudinal 35 grooves 19 which constitute seats to receive the work. This presser piece is formed with a plurality of faces and each of the faces has a groove 19 therein. The presser piece 18 may be adjusted to bring any one of its 40 faces in position to coöperate with a form so as to bend the material therearound. An operating lever 20 has one end bifurcated to embrace the upper and lower sides of the frame to which it is pivotally connected by 45 means of a bolt or pin 21. Links 22 and 23 connect opposite ends of the presser piece 19 to the lever 20 and an auxiliary lever 24, the latter being pivotally connected to the lever 20. The link 22 and auxiliary lever 50 24 are adapted to be adjustably connected with the lever 20, thereby making provision for proper adjustment of the presser piece to suit the work and the selected form. A bearing 25 carried by the lever 24 is adapted 55 to engage a side of the presser piece 18 to properly adjust the same with reference to the work. The bearing 25 has the end adapted to engage the presser piece 18 made round and such bearing is preferably 60 formed separate from the lever 24 and attached thereto although such arrangement is not essential. The levers 20 and 24, together with the presser piece 18, bearing 25

and links 22 and 23, constitute the shaping means whereby the work is adapted to be bent around the form. The shaping means may be shifted from one end of the machine to the other and is adjustable in the manner stated to be readily adapted to the size of the form and the character of the work. 70 The shaping mechanism is connected to the frame by means of the fastening 21 in the manner stated and is further supported by means of a curved bar 26 which may be attached to the frame in any manner. 75

In the modification shown in Fig. 5 the form 27 has its active portion curved but such form is not necessarily circular. The form may be attached to plates 28 which in turn are adapted to be secured to the 80 frame of the machine in any manner. An operating lever is mounted upon the plates 28 in the manner hereinbefore described and is adapted to coöperate with jaws in the manner stated for holding the work. In 85 the operation of the machine the work to be bent is secured to one side of the machine or the other as may be desired and the end to be bent about the form is engaged by means of the presser piece 18 and by proper 90 manipulation of the levers 20 and 24 the end of the work projecting beyond the form is bent about such form, the shape and degree of curvature being determined by the curved edge and diameter of the form. By 95 shifting the work from one side of the machine to the other or from one end of the machine to the opposite end of the machine and by placing forms of different size and shape in position the work may be caused to 100 assume various curves according to the design and configuration of the article to be constructed.

Having thus described the invention, what is claimed as new is:—

1. In a machine of the character described, a work-holder comprising coöperating jaws, one of such jaws being movable, an operating lever having an end portion bifurcated and provided with hubs, a bearing 110 having such hubs mounted therein, and connecting means for the movable jaw having eccentric connection with the hubs and passing between the bifurcations of the lever.

2. In a machine of the character described, a work-holder comprising coöperating jaws, an operating lever having an end portion bifurcated and having the bifurcations formed on the outer sides with hubs, a bearing receiving such hubs, and a connection 115 between the operating lever and movable jaw, such connection passing between the bifurcations of the lever and having eccentric connection therewith.

In testimony whereof I affix my signature.
JOHN S. WHEELER. [L.S.]
